UNITED STATES PATENT OFFICE.

FREDERICK M. TURCK, OF NEW YORK, N. Y., ASSIGNOR TO THE CARTER-CRUME COMPANY, LIMITED, OF TORONTO, CANADA, A CORPORATION OF ONTARIO.

DELIVERY MECHANISM FOR WEB-PRINTING PRESSES.

1,153,833.

Specification of Letters Patent. Patented Sept. 14, 1915.

Application filed October 10, 1911. Serial No. 653,806.

To all whom it may concern:

Be it known that I, FREDERICK M. TURCK, a citizen of the United States, and resident of New York, in the county of New York 5 and State of New York, have invented certain new and useful Improvements in Delivery Mechanism for Web-Printing Presses, of which the following is a specification.

The invention relates to improvements in 10 delivery mechanism for web printing presses, and has particular reference to machines in which the web after being printed and numbered in series is cut into sheets and folded for the formation of books; and 15 the objects of the invention are to provide means for collecting the folded sheets, dividing the same into series corresponding with the printed numbers thereon, and delivering the sheets thus divided in a sym- 20 metrical manner with their edges in exact alinement; and further objects comprehend certain details of construction and arrangement of parts, including means readily adjusted by which the number of sheets comprising a series may be varied, and the dividing means likewise adjusted with respect thereto.

In describing the invention in detail reference is had to the accompanying drawings, 30 forming a part of this specification, wherein similar characters of reference are used to designate like parts throughout the several views, and in which:

Figure 1 is a front elevation of a portion 35 of a printing press shown in connection with a folder containing the improved delivery device, a portion of the delivery-table being removed to show more clearly certain parts of the mechanism; Fig. 2, an end elevation, partially in section, of the folder including the collecting, dividing and delivery devices; Fig. 3, a ground plan, partially in 40 section, of the delivery in connection with the collecting and dividing devices; Fig. 4, an enlarged detail view of a portion of the delivery device taken with a section of the sheet controller; Fig. 5, a similar view of the delivery device shown in connection with the sheet spacer; Fig. 6, an end view of a portion 45 of the latter; Fig. 7, a front elevation of a portion of the sheet-dividing device; Fig. 8, a rear view of the latter; and Fig. 9,

is an enlarged detail side view of the sheet detent.

In the drawings, numeral 1 designates a 55 portion of the framework of an ordinary printing press, in which are rotatably mounted the cutting rolls 2, arranged to transversely sever into sheets the previously printed web 3.

Numerals 4 and 5 designate respectively 60 the front and rear frames of the folder and delivery device, the front frame having a delivery-table 6 secured thereto. Rotatably mounted in the frames are a series of guide 65 pulleys 7, carrying an upper and lower set of endless narrow bands or tapes 8 and 9, between which sets of tapes the severed sheets are conveyed in the usual accelerated manner to the folder. Between the frames 70 is fixed a bearing-plate 10, which not only acts as a bearing for the lower set of tapes but also serves as a support for the sheet. Centrally of its width the plate is provided 75 with a slot 11, through which is arranged to pass the vertically-reciprocating folding-blade 12, secured to the head 13, mounted for sliding movement in the bracket 14, secured to the cross-beam 15, carried by the frames 4 and 5. For effecting the driving 80 movement of the blade, the head is provided with side lugs to form a groove, in which is arranged the driving-eccentric 16, fixed to the shaft 17, the latter being mounted in bearings formed in the frames 85 and provided with a fixed drive-wheel 18, adapted to receive its motion from a convenient rotating shaft on the press. Co-acting with the blade 12 for folding the sheets are a pair of folding-rollers 19, rotatably mounted in the frames in the usual manner.

Below the folding rollers 19 and suitably mounted for rotation in the frames, are a 90 pair of shafts 20 and 21, each of which is provided with a fixed continuous spiral blade having a plurality of convolutions, constituting a screw-conveyer, the blades of the conveyers being preferably of thin metal and, as herein shown, overlapping each 95 other in close relation, the pitch thereof providing sufficient space to permit the free admission of the folded sheets 3^a, delivered from the folding-rollers. Gear-wheels 22

are fixed upon the conveyer-shafts and are driven in a common direction by their engagement with the gear 23, fixed to the shaft 24, which in turn is rotatably mounted 5 in the bearing 25 in the frame 5. A chain-wheel 26 is fixed upon shaft 24 and motion is transmitted thereto through the chain 27 and the wheel 28, the latter being fixed upon the shaft 17, which serves by suitably 10 proportioning the above gearing to drive the folding blade and the screw-conveyers at a common rate of speed to effect a revolution of the latter for each folded sheet. For controlling the passage of the sheets from 15 the folding-rollers to the conveyers, fixed guide-strips 29 are provided and disposed to direct the sheets to the conveyer-shafts between the blades of the initial or rearward end of the conveyers, the free upper ends 20 of the sheets being forwardly deflected at this point to afford a clearance for the succeeding sheets. This forward deflection is effected by the blades 30, fixed upon the rotatable shaft 31, suitably journaled in the 25 frame, the blades of the deflector being of sufficient length and suitably spaced upon the shaft to engage the free ends of the sheets and to escape the spaced guide-strips 29. At their forward ends the conveyer- 30 shafts are provided with reduced journals, mounted in boxes 32, secured in such manner to the delivery-table 6 that the sheets may be freely delivered upon the latter in opposition to the slidable stop-board 33, 35 which serves to maintain the regularity of the delivered sheets.

As indicated in Fig. 1, the rotation of the conveyers is in a common direction, which movement of the several blades there- 40 of serve to urge the sheets separately against a traveling stop, comprising a pair of endless belts 34, carried by rollers 35, journaled in suitably-positioned brackets and arms mounted on the frames. By a convenient 45 band 36, the stop-belts are driven at a rate of speed corresponding substantially with the movement of delivery of the sheets. As the bottom edge of the folded sheets rest upon the rotatable conveyer-shafts and the 50 blades thereof throughout their several convolutions frictionally engage the successive sheets separately, it will be obvious that not only will the sheets be effectively urged toward and held with their forward or 55 head ends against the traveling stop-belts for lateral adjustment but the bottom edges of this portion of the sheets will likewise be held down upon their support to pre- 60 serve an exact alinement of these several edges. At the forward or delivery end of conveyer-shaft 20, the blade thereon is reduced in diameter to present a clearance for the inwardly-extending sheet-detent or support 37, secured upon the delivery table 65 6 with their upper faces respectively in line.

The detent comprises a wire toothed comb, or brush having a suitable backing, as shown in the enlarged view Fig. 9, and resembling an ordinary card, having the ends of their teeth forwardly bent in the direction of the 70 movement of the sheets and with the bottom edges of which they engage and permit a free forward movement thereof while offering sufficient resistance in the opposite direction to prevent any backward movement 75 thereof. For a like purpose similar detents 38 and 39 are provided and disposed to engage the edges of the delivered sheets adjacent the delivery end of the conveyers.

While the heads of the sheets are maintained in adjustment at the delivery end of the conveyer by the normal rotation of the latter, their opposite or foot-ends have, in some instances where large sheets are required, a tendency to be disturbed at the 80 corresponding delivery point by the upward rotative movement of the blade on the conveyer-shaft 21, and to obviate this action of the blade-end a controller is provided, including a lever-arm 40, pivotally mounted 85 intermediate its ends on the fulcrum-pin 41, secured to the inside of frame 4. For actuating this arm a connecting-rod 42 is pivotally connected at one end to the upper end 90 of the former at the point 43, while the opposite end of the rod is provided with a strap 44, surrounding an eccentric 45, fixed upon the shaft 17, which effects a backward and forward reciprocation of the lever-arm 95 at each rotation of the conveyer-shaft. At the lower end of the arm are secured 100 resilient spring-metal fingers 46 and 47, which reciprocate back and forth, as indicated by the dotted lines in Fig. 1, and the free ends thereof bear directly upon the surface of the conveyer-blade. Upon their upward movement the fingers pass between the sheet and conveyer-blade and separate the sheets from the blade, overcoming thereby the lifting 105 tendency of the latter upon the foot portion of the sheets. In its rotation the spiral conveyer-blade forwardly bends the several resilient fingers, engaging the same gradually at points nearing their connection ends, and effecting a spacing between the free 110 ends thereof and the conveyer-blade for the separation of the sheets from the latter. At about the beginning of their downward movement the fingers are released from the delivery end of the conveyer and spring 115 back against the succeeding sheet, serving to hold the same against its respective portion of the conveyer and urge it downwardly in opposition to the upward motion of the latter. The blade at the delivery end of the conveyer is provided with an open slot 120 48, which is adapted to receive and release finger 47, operating on the upper portion of the sheets, at an earlier period than that 125 for fingers 46 which act upon the lower por- 130

tion thereof, the latter fingers serving at this period to advance the foot portion of the delivered sheet while finger 47 urges the succeeding undelivered sheet in the opposite direction against the conveyer-blade, as more clearly shown in Fig. 4. It will be evident that the regularity of adjustment of the sheets as delivered from the conveyer may be readily controlled by the action of the fingers which serve the double purpose of urging the undelivered sheets downward successively and spacing the same after delivery beyond the disturbing action of the upwardly-moving blade-end. To further insure this separation from the conveyer, a spacer is provided which engages the foot ends of the delivered sheets at their bottom edges successively and serves to further advance the same from the position obtained by the flexible fingers. As shown in Figs. 1, 3, 5 and 6, the spacer comprises a swinging dog 49, hinged by the pin 50 to the head 51 and normally held in a vertical position thereon by a coil-spring 52, which surrounds the pin, the ends of the spring respectively engaging the head and the dog and urging the latter backward to the limit of its movement controlled by the stop-lug 53, formed thereon and arranged for engagement with the head in a recess formed in the latter. The head is supported for horizontal reciprocation by the integral stem 54, slidably mounted in the box 55, the stem being constructed with a reduced terminal portion to provide a shoulder therefor within the box and to slidably receive a compression-spring 56, the ends of which respectively engage an end wall of the box and the shoulder of the stem to normally urge the head and its connected dog in the direction of the conveyer. For the further support of the spacer, the box 55 is secured to one end of a lever 57, pivotally mounted intermediate its ends upon a pin 58, fixed to the delivery-table 6, the opposite end of the lever being engaged by a drive-pin 59, fixed to a disk formed on the forward end of conveyer-shaft 21 exteriorly of its reduced journal. A fixed stop 60 is provided for the engagement of the actuating end of the lever for limiting the downward movement thereof, and to the latter is secured one end of a tension spring 61, the opposite end being conveniently fixed to the delivery table. For affording a clearance between the spacing-dog and the conveyer-blade for the reception of the successive sheets at their point of delivery, the spacer-head 51 is provided with a projecting lug 62, which engages the blade below the bottom line of the sheets, and also serves as a contact point to receive the thrust of the conveyer at each revolution thereof for the advancement of the spacing head and dog in opposition to the compression spring 56, which latter at the terminal edge of the

conveyer is free to backwardly move or return the dog. At about the beginning of this backward movement the drive-pin 59 on the end of the conveyer-shaft engages the actuating-arm of lever 57 and depresses the spacing-dog 49 against the action of the tension-spring 61. As thus depressed the rearward top portion of the dog engages the sheet about to be delivered and the terminal edge of the conveyer, the latter serving as an abutment in connection with spring 56 to forwardly turn the dog about its hinge-pin 50 in opposition to the coil-spring 52. By this turning movement of the dog its downward motion or depression may be limited, and its backward or return movement readily accomplished, in which latter relation by the reaction of the hinge-spring the dog will assume its normal upright position behind the following sheet and serve to advance the same in the manner heretofore described.

For dividing the sheets into series corresponding with the printed numbers thereon, a plurality of division-cards 63 are employed which are supplied to the machine at the rear of the conveyers and supported edgewise upon a pair of cam-shafts 64 and 65, mounted for intermittent rotation in bearings 66, formed in the rear frame. For transmitting motion to cam-shaft 64, a ratchet-wheel 67 is fixed thereon and actuated from the conveyer-shaft 20 by an eccentric 68, fixed to the outer end of the latter and engaging a roller 69 journaled upon a rocker arm 70, the latter being loosely mounted upon the shaft 64 and provided with a pawl 71, which engages the teeth of the ratchet-wheel for the rotation thereof. For driving the opposite cam-shaft 65, a chain-wheel 72 is secured to the rearward end thereof, and motion is transmitted thereto through the chain 73, the chain-wheel 74, and the interengaging gear-wheels 75 and 76, the latter wheel being fixed upon cam-shaft 64, and the wheels 74 and 75 fixed together and loosely mounted upon the conveyer-shaft 20. As thus arranged and suitably proportioned the gearing is designed to provide for the two cam-shafts a uniform rate of angular rotation in opposite directions. Upon the forward ends of the cam-shafts are secured disks 77, each provided with a fixed cam-plate 78, having a thickness substantially equal to that of one of the several division-cards 63, and against which the latter are successively urged by the follower-board 79, slidably mounted on the several adjacent shafts and forwardly urged by the weight 80, connected thereto by the flexible band 81, passing over a conveniently-mounted guide-pulley 82. The division-cards are composed of sufficiently resistant material to maintain their shape without appreciable flexure, and are adapted to be

sufficiently raised by their engagement at their bottom edges with the cam-plates 78 at each revolution thereof to slide into the feed ends of the conveyers. At their delivery points the cam-plates are transversely beveled, which shape, together with the correspondingly beveled edges of the disks 77, facilitates the feeding action of the cards, this action being furthermore accelerated by the angularly-disposed fixed deflector 83 which engages the upper edge of an upwardly moving card and serves by rearwardly directing the same against the upper edge of the adjacent stationary card to forwardly urge its bottom edge into the feed ends of the conveyers, the blades thereof being terminally reduced in diameter, as shown in Fig. 7, for the accommodation of the feeding action. The deflector 83 is secured upon a bar 84, carried by the frames of the machine, and to the bar are also secured a number of pendent friction-fingers 85, composed of thin spring material, adapted at their free ends to frictionally engage and arrest the excessive forward movement of the upper edges of the division-cards as fed to the conveyers to afford a clearance for the incoming final folded sheet of the series. As the ends of the friction-fingers extend only slightly below the line of the upper edge of the division-card, the latter as forwardly moved by the conveyer will readily overcome the slight resistance offered by the fingers and be carried along and delivered with the sheets.

In the division and delivery of the sheets, it will be clear that for each throw of the eccentric 68 or forward movement of the pawl 71 a sheet will be fed to the conveyer, and that the desired number of sheets in the series must equal the number of teeth in the ratchet-wheel 67 or be a factor thereof: Thus, if one hundred sheets are required for a series the ratchet-wheel will contain one hundred teeth and be operated one tooth by each throw of the eccentric; and if fifty sheets are required for the series the same ratchet-wheel may be utilized but must be advanced two teeth by the eccentric, necessitating a correspondingly increased throw of the latter. For indicating the numbered sheets in a series as fed to the conveyer with respect to the number of teeth on the ratchet-wheel, the latter is provided with corresponding dial-lines or numbers adapted to register with the actuating pawl, and for timing the feed of the division-cards to effect the required division of the sheets as numbered a manually-operated handle 86 is secured to the outer end of cam-shaft 64 and serves to rotate the same, independently of its normal rotating means, and adjust the numbered teeth of the ratchet-wheel with respect to the pawl; and if for any reason the sheets in the series become disarranged

with respect to the division-cards, it will be readily seen that a proper adjustment therebetween may be quickly made by means of the above handle.

As the operation of the various parts has been set out in detail and in the connection wherein they coöperate with each other it is believed a recapitulation of the entire operation is unnecessary.

It is apparent, of course, that while I illustrate and describe the preferred embodiment of the invention it is susceptible of various changes as regards its form, proportion, detail construction, and arrangement of parts without departing from the essential principle or scope of the invention; thus, in cases requiring the delivery of particularly wide sheets, a set containing three or more conveyers may be employed instead of the pair shown.

What I claim as my invention and desire to secure by Letters Patent, is:

1. In a sheet delivery device, in combination, folding mechanism for folding a sheet, a delivery device, connected with said folding mechanism comprising a set of rotary screw conveyers disposed to receive folded sheets and convey the same in the direction of the length of said set, and a movable stop device disposed at the side of the conveyer to receive the lateral thrust exerted on said sheets by the rotation of said screw conveyers.

2. In a sheet delivery device, in combination, means for folding a sheet, a delivery device comprising a set of rotatable screw conveyers disposed to receive said sheets and move them in the direction of the length of the conveyer, a stop at the end of said delivery device, and a moving stop disposed to receive the lateral thrust exerted upon the sheets by the rotation of the screw conveyers.

3. In a sheet delivery device, in combination, means for folding a sheet, a delivery device comprising a set of rotatable screw conveyers disposed to receive said sheets, a stop at the end of said conveyers, and a belt moving in the direction of movement of the folded sheets adapted to maintain their alignment.

4. The combination of a device for cutting a printed web into multiple series of sheets, means for separately folding said sheets, means comprising a set of rotatable screw-conveyers disposed to receive and deliver said folded sheets, a support for a plurality of division-cards adjacent said screw-conveyers, and means for feeding said cards thereto for separating said multiple series, substantially as set forth.

5. A sheet delivery device comprising a set of rotatable screw conveyers, means for feeding sheets thereto, means for rotating said conveyers in a direction to advance said

- sheets, and a belt movable in the direction of the moving sheets adapted to coact and maintain the alinement of their side edges while being carried by said conveyers.
5. 6. A sheet delivery device comprising a set of rotatable screw conveyers, means for feeding sheets thereto, means for rotating said conveyers in a direction to advance said sheets, a belt movable in the direction of the moving sheets adapted to coact and maintain the alinement of their side edges, and means for separating the sheets at regular intervals.
10. 7. A sheet-delivery device comprising a set of rotatable screw-conveyers, means for feeding a multiple series of sheets thereto, a support for a plurality of division-cards adjacent said conveyers, and means for feeding said division-cards thereto for separating said multiple series of sheets.
15. 8. A sheet-delivery device comprising a set of rotatable screw-conveyers, means for feeding a multiple series of sheets thereto, a support for a plurality of division-cards adjacent said conveyers, means actuated by a positively-moving part for feeding said division-cards to the conveyers, and means operated independently of said positively-moving part for timing said feed mechanism.
20. 9. In a sheet-delivery device, the combination with a rotatable screw conveyer disposed to collect and deliver a multiple series of sheets, of a cam rotatably mounted adjacent said conveyer and provided with a delivery portion coacting with the feed end of said conveyer, means supporting a plurality of division-cards for engagement with said cam, and means actuated by the movement of said conveyer for imparting intermittent rotary movement to said cam.
25. 10. In a sheet-delivery device, the combination with a set of screw-conveyers connected together for rotation and disposed to collect and deliver a multiple series of sheets, of a pair of cam-shafts rotatively connected together, cams secured to the inner ends of said cam-shafts and provided with delivery portions coacting with the feed ends of said conveyers, means supporting a plurality of division-cards for engagement with said cam, a ratchet-wheel fixed to one of said cam-shafts, and means actuated by the movement of the conveyers for operating said ratchet-wheel.
30. 11. In a sheet-delivery device, the combination with a set of screw-conveyers connected together for rotation and disposed to collect and deliver a multiple series of sheets, of a pair of cam-shafts rotatively connected together, cams secured to the inner ends of said cam-shafts and provided with delivery portions coacting with the feed ends of said conveyers, means supporting a plurality of division-cards for engagement with said cam, a ratchet-wheel fixed to one of said cam-shafts, means actuated by the movement of the conveyers for operating said ratchet-wheel.
35. 12. In a sheet delivery device, in combination, a rotatable screw conveyer, a delivery table positioned at one end thereof, and a wire toothed detent on said table adjacent the end of said conveyer to coact with the edges of the sheets to hold them out of engagement with the conveyer after being delivered therefrom.
40. 13. In a sheet delivery device, in combination, a conveyer mechanism, a delivery table positioned at the end thereof, a plurality of detents carried by the said table each comprising a wire toothed comb the teeth of which are bent in the direction of the delivery of said sheets whereby they engage their lateral edges at several points to hold them out of engagement with the conveyer after being delivered therefrom.
45. 14. In a sheet delivery device, in combination, a conveyer, a table positioned at the delivery end thereof, and a wire toothed comb positioned on said table in line substantially with the center of said conveyer adapted to engage the middle of the bottom edge of the delivered sheets to prevent retraction thereof.
50. 15. In a sheet delivery device, in combination, a receiving table and a detent mounted thereon comprising a wire toothed comb provided with a suitable backing and having the free ends of the teeth bent in the direction of delivery.
55. 16. In a sheet delivery device, in combination, a rotatable screw conveyer, and means coacting with the final turn of said conveyer adapted to separate the sheets from said final turn to prevent the same being carried upwardly and around thereby.
60. 17. In a sheet-delivery device, the combination of a rotatable screw-conveyer, a sheet-controller comprising a plurality of fingers supported for yielding engagement with the delivery-end of said screw-conveyer, and means for varying severally the period of engagement of said fingers.
65. 18. In a sheet-delivery device, the combination of a rotatable screw-conveyer, a sheet-controller comprising a plurality of spring-fingers supported for engagement with the delivery-end of said screw-conveyer, and means for imparting a vertical movement to said fingers.
70. 19. In a sheet-delivery device, the combination with the delivery-end of a screw-conveyer, of a lever-arm pivotally mounted adjacent thereto, a plurality of spring fingers carried by the lever-arm and engaging said conveyer-end, and means for oscillating said lever-arm.

20. In a sheet-delivery device, the combination with the delivery-end of a screw-conveyer, of a sheet-spacing dog mounted for yielding engagement therewith and adapted 5 to engage the rear of the delivered sheets successively and hold them out of contact with the final turn of the conveyer. 70
21. In a sheet-delivery device, the combination with the delivery-end of a screw-conveyer, a supporting-box vertically movable 10 adjacent thereto, a sheet-spacing dog slidably mounted in said box and adapted to engage the rear of the delivered sheets successively, and a spring in said box arranged 15 to yieldingly urge said dog into engagement with said screw-conveyer. 75
22. In a sheet-delivery device, the combination with the delivery-end of a screw-conveyer, of a plurality of vertically-movable 20 spring-fingers adjacently mounted for engagement therewith, and a sheet-spacing dog mounted for yielding engagement with said conveyer and adapted to engage the rear of the delivered sheets successively. 85
23. In a sheet delivery device, in combination, a rotatable screw conveyer, a support 25 for a plurality of division cards adjacent one end of said conveyer, and means for feeding the divisional cards to said conveyer at 30 regular intervals. 90
24. In a sheet delivery device, in combination, a double screw conveyer, a support for a plurality of division cards adjacent one end thereof, stop means interposed between 35 the cards and the conveyer, and means for raising the cards over said stop. 95
25. In a sheet delivery device, in combination, a conveyer means adapted to carry a folded sheet to a receiving table, a support for 40 a plurality of division cards adjacent one end of said conveyer, and means for driving the conveyer and simultaneously delivering the division cards thereto at regular intervals to be carried with the folded sheets to a 45 delivery table. 100
26. In a sheet delivery device, in combination, a conveyer adapted to carry a plurality 50 of sheets positioned on one edge thereof, means for maintaining the alinement of said sheets, a support for a plurality of division cards, and means for simultaneously driving the conveyer and the guiding means and also feeding the cards to the conveyer at regular 55 intervals. 110
27. In a sheet delivery device, in combination, a conveyer, a receiving table at one end thereof and a support near the opposite end for holding a plurality of division cards, 60 means for feeding the folded sheets to said conveyer, means extending along one side of the conveyer for maintaining the alinement of the folded sheets, means for feeding the division cards at regular intervals to the conveyer, and means for simultaneously driving 65 these mechanisms. 115
28. In a sheet delivery device, in combination, a conveyer, a receiving table at one end thereof and a support near the opposite end for holding a plurality of division cards, 70 means for feeding the folded sheets to said conveyer, means extending along one side of the conveyer for maintaining the alinement of the folded sheets, means for feeding the division cards at regular intervals to the conveyer, means for simultaneously driving 75 these mechanisms, and means adjacent the end of the conveyer for holding said division cards in compact relation. 80
29. In a sheet delivery device, in combination, a screw conveyer, a receiving table 85 near one end thereof, a support for a plurality of division cards near the opposite end, means for holding the division cards in compact relation, means for feeding the cards at regular intervals to the screw-conveyer and between the sheets carried thereby, and means at the opposite end of the conveyer adjacent the edge of the receiving table for holding the folded sheets and division cards out of contact with the final 90 turn of the conveyer. 95
30. In a sheet delivery device, in combination, means for cutting a web into sheets, means for folding the sheets transversely, a screw conveyer, means for feeding the folded sheets to the conveyer, movable means for maintaining the alinement of the sheets while being carried by the conveyer, means for feeding division cards to the conveyer and between the sheets carried thereby at 100 regular intervals, and means coacting with the final turn of the conveyer for preventing the sheets from being carried upwardly by the final turn thereof when delivered from the conveyer. 105
31. In a sheet delivery device, in combination, means for cutting a web into sheets and folding the sheets transversely, a screw conveyer, means for feeding the folded sheets to the conveyer, movable means for maintaining the alinement of the sheets while being carried by the conveyer, means for feeding division cards to the conveyer and between the sheets carried thereby at regular intervals, a receiving table near the delivery end of said conveyer, and means coacting with the final turn of the conveyer for moving the sheets out of engagement therewith. 110
32. In a sheet delivery device, in combination, means for cutting a web into sheets and folding the sheets transversely, a screw conveyer, means for feeding the folded sheets to the conveyer, movable means for maintaining the alinement of the sheets while being carried by the conveyer, means for feeding division cards to the conveyer and between the sheets carried thereby at regular intervals, a receiving table near the delivery end of said conveyer, means coact- 120
- 125
- 130

ing with the final turn of the conveyer for moving the sheets out of engagement therewith, and means on said delivery table for holding the leaves against retraction when delivered thereto.

33. In a sheet delivery device, in combination, means for cutting a web into sheets, means for folding the sheets transversely, a screw conveyer, means for feeding the folded sheets to the conveyer, movable means for maintaining the alinement of the sheets while being carried by the conveyer, means for feeding division cards to the conveyer and between the sheets carried thereby at regular intervals, a receiving table near the delivery end of said conveyer, means coacting with the final turn of the conveyer for moving the sheets out of engagement therewith, and a toothed comb positioned upon said table engaging the edges of said sheets to prevent retraction thereof.
34. In a sheet delivery device, in combination, means for cutting a web into sheets and subsequently folding same transversely, a screw conveyer adapted to receive the folded sheets, a movable guide for maintaining the alinement of the edges of said sheets, and means for feeding division cards thereto at regular intervals, all of said means being connected, whereby they operate simultaneously.
35. In a sheet delivery device, in combination, a cutter for severing a web into sheets, a folder adapted to engage the sheets, a screw-conveyer positioned beneath the

folder for receiving the folded sheets, a receiving table near the end of the conveyer, a support near the opposite end of the conveyer adapted to hold a plurality of division cards, means for holding said division cards 40 in compact relation, means geared with the folder mechanism for feeding the division cards to the conveyer at regular intervals, and spring fingers coacting with the final turn of the conveyer for moving the leaves 45 out of contact therewith when delivered.

36.
